UNITED STATES PATENT OFFICE.

JOHN GIBBONS ROBERTS, OF HOLLY SPRINGS, MISSISSIPPI.

PICTURE-FRAME.

1,194,238.

Specification of Letters Patent.

Patented Aug. 8, 1916.

Application filed April 8, 1916. Serial No. 89,825.

To all whom it may concern:

Be it known that I, JOHN G. ROBERTS, a citizen of the United States, and a resident of Holly Springs, in the county of Mar-
5 shall and State of Mississippi, have invented a new and Improved Picture-Frame, of which the following is a full, clear, and exact description.

My invention has for its object to provide
10 a frame constructed of a member which may be glass and heart shaped, around which there is disposed a ladder chain, the links of which engage both sides of the member at the member's edge, the ladder chain being
15 held in place in the recess at the top of the heart by a wire which is secured to the chain at the bottom of the heart.

Additional objects of the invention will appear in the following specification in
20 which the preferred form of my invention is disclosed.

In the drawings similar reference characters refer to similar parts in all the views in which—

25 Figure 1 is a front view of my improved frame; Fig. 2 is a rear view of the frame; and Fig. 3 is a side elevation with parts broken away to illustrate the construction.

By referring to the drawings it will be
30 seen that a heart shaped member 5 is provided to which may be secured a mirror or picture, a ladder chain 6 being disposed around the edge 7 of the member 5. This chain 6 is of the ladder type, each of the
35 links being constructed with a transverse member 8 from which extends arms 9 having eyes 10 at their terminals, through which is disposed a transverse member on an adjacent link. The eyes 10 engage the opposite
40 sides of the member 5 at its edge and serve to prevent the displacement of the chain 6.

When the chain 6 is disposed around the edge 7 of the member 5, a wire 11 is secured to the chain 6 at the recess 12 in the member 5, and by a hook 15, this wire 11 extending 45 down to the bottom of the member 5 and being secured at 13 to the bottom of the chain 6 by a hook 16. In this way the chain 6 is drawn snugly against the edge 7 of the member 5 with the eyes 10 disposed against 50 the sides of the said member at its edge. With this construction the chain is held securely in place and to this chain may be attached another chain 14 by which the frame may be hung. 55

Having thus described my invention I claim as new and desire to secure by Letters Patent:

1. In an article of the class described, a heart shaped member, a ladder chain disposed around the edge of the member, and engaging the opposite sides of the member at its edge, and a wire secured to the chain at the recess in the top of the heart, the wire extending to the bottom of the heart and 60 being secured to the chain adjacent thereto. 65

2. In an article of the class described, a member having an edge, a chain having links, each of which has a transverse member disposed across the edge of the member, 70 and two eyes through which a transverse member on an adjacent link is disposed, the eyes being disposed one at each side of the member for holding the chain in position.

In testimony whereof, I have signed my 75 name to this specification in the presence of the two subscribing witnesses.

JOHN GIBBONS ROBERTS.
